(57) CLAIM

The ornamental design for a wheel front face, as shown and described.

DESCRIPTION

FIG. 1 is a perspective view of a wheel front face, showing my new design;

FIG. 2 is a front view thereof; and,

FIG. 3 is a side view thereof.

In the drawings, the broken lines depict environmental subject matter and form no part of the claimed design.

1 Claim, 3 Drawing SheetsFIG. 1

FIG. 3
